(57) **CLAIM**

We claim the ornamental design for a ball head of a tripod for an electronic device, as shown and described.

DESCRIPTION

FIG. 1 is a perspective view of a ball head of a tripod for an electronic device;
FIG. 2 is a front view thereof;
FIG. 3 is a rear view thereof;
FIG. 4 is a right side view thereof;
FIG. 5 is a left side view thereof;
FIG. 6 is a top plan view thereof;
FIG. 7 is a bottom plan view thereof; and,
FIG. 8 is an alternate perspective view thereof.

The evenly spaced broken lines in FIGS. 1-6 and 8 are used to illustrate unclaimed portions of the ball head of a tripod for an electronic device. The dash-dot-dash broken lines in FIGS. 2-5 and 7 depict the bounds of the claimed design. The dash-dot-dash broken lines in FIG. 8 are used to illustrate environment. The broken lines form no part of the claimed design.
